UNITED STATES PATENT OFFICE

135,299

DESIGN FOR AN ELECTRIC LAMP BULB

John J. Devine, Middletown, Conn.

Application November 25, 1942, Serial No. 108,877

Term of patent 14 years

To all whom it may concern:

Be it known that I, John J. Devine, a citizen of the United States, residing at Middletown, in the county of Middlesex and State of Connecticut, have invented a new, original, and ornamental Design for an Electric Lamp Bulb, of which the following is a specification, reference being had to the accompanying drawing, forming part thereof.

In the drawing:

Fig. 1 is a side elevational view of an electric lamp bulb, showing my design;

Fig. 2 is a front elevational view thereof;

Fig. 3 is a bottom plan view.

Fig. 4 is a longitudinal sectional view through the lamp bulb.

I claim:

The ornamental design for an electric lamp bulb, as shown.

JOHN J. DEVINE.
